PLATE OR SIMILAR ARTICLE

Shigeru Masuda, 2486 8th St., Apt. E,
Fort Lee, N.J. 07024

Filed Jan. 17, 1966, Ser. No. 625
Claims priority, application Japan Aug. 11, 1965

Term of patent 7 years

(Cl. D44—15)

The figure is a plan view of a plate or similar article showing my new design, a portion of the design being shown between dotted lines and a repeat portion being shown between dot-and-dash lines.

The plate is of a conventional configuration when viewed from the side and bottom thereof.

I claim:

The ornamental design for a plate or similar article, substantially as shown and described.
